UNITED STATES PATENT OFFICE.

DANIEL E. REAGAN, OF COLUMBUS, OHIO, ASSIGNOR TO HOCKING VALLEY PRODUCTS COMPANY, OF COLUMBUS, OHIO, A CORPORATION OF WEST VIRGINIA.

DESIGN FOR A BRICK OR SIMILAR ARTICLE.

46,580.

Specification for Design.

Patented Oct. 20, 1914.

Application filed May 22, 1914. Serial No. 840,389. Term of patent 14 years.

To all whom it may concern:

Be it known that I, DANIEL E. REAGAN, a citizen of the United States, residing at Columbus, in the county of Franklin and State of Ohio, have invented a new, original, and ornamental Design for a Brick or Similar Article, of which the following is a specification, reference being had to the accompanying drawing, forming part thereof.

The figure is a perspective view of a brick or similar article, showing my new design.

The design consists in parallel furrows over the face of the brick, the furrows being more or less obliterated by a distribution

over them of the material furrowed up but leaving parts of some or all the furrow visible at intervals over the face of the brick, whereby an irregular roughened surface approximating in appearance, a rug like texture is produced.

I claim:—

The ornamental design for a brick, or similar article, as shown and described.

DANIEL E. REAGAN.
